UNITED STATES PATENT OFFICE

163,516

TERMINAL CAP

Benton A. Gruver, North Hollywood, and Archibald Robertson, Burbank, Calif., assignors to Los Angeles Standard Rubber, Inc., Los Angeles, Calif., a corporation of California

Application July 21, 1950, Serial No. 11,208

Term of patent 3½ years

(Cl. D26—1)

To all whom it may concern:

Be it known that we, Benton A. Gruver and Archibald Robertson, citizens of the United States, residing respectively at North Hollywood and Burbank, county of Los Angeles, State of California, have jointly invented a new, original, and ornamental Design for a Terminal Cap, of which the following is a specification, reference being had to the accompanying drawing, forming a part thereof:

Fig. 1 is a perspective view of a terminal cap showing our new design.

Fig. 2 is an end elevational view of said cap.

Fig. 3 is a side elevational view of Fig. 2.

Fig. 4 is a plan view of said cap.

Fig. 5 is a bottom plan view of said cap.

We claim:

The ornamental design for a terminal cap, as shown.

BENTON A. GRUVER.
ARCHIBALD ROBERTSON.
